(57) **CLAIM**

I claim the ornamental design for a shark shape slipper, as shown and described.

DESCRIPTION

FIG. 1 is a front perspective view of a shark shape slipper showing my ornamental design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom perspective view thereof; and,

FIG. 8 is another bottom perspective view thereof.
